BAG PRESSURE INDICATOR FOR SUCTION
CLEANERSDale C. Gerber, North Canton, Ohio, assignor to
The Hoover Company, North Canton, Ohio, a
corporation of Ohio

Application December 5, 1938, Serial No. 244,006

6 Claims. (Cl. 116—65)

This invention relates to improvements in bag pressure indicators for suction cleaners and more particularly to an indicator designed to register the increased pressure within the dirt or filter bag of a suction cleaner, and for the purpose of warning the operator when the contents of the bag should be emptied.

The object of the invention is to provide a comparatively simple and inexpensive type of pressure indicator characterized primarily by the fact that it is carried directly by the bag and responds to the variations in pressure therein by yieldingly resisting the tendency of the bag to expand as the internal pressure is increased.

15 And a further object of the invention is to provide a type of bag pressure indicator which is not only carried by the bag but has detachable mounting thereon so that as one bag becomes worn and discarded, the indicator can be removed therefrom and attached to a new bag.

A preferred embodiment of the bag pressure indicator hereinabove described, will now be disclosed in connection with the accompanying drawing, in which:

25 Figure 1 is a perspective view of a suction cleaner showing the location and general arrangement of the indicator;

Figure 2 is an enlarged view in perspective of the indicator removed from the bag and with 30 sections broken away to show its construction; and

35 Figure 3 is a detailed view taken in cross section through the bag at the point of attachment of the indicator and showing the relative positions of its telescoping parts under normal and excessive pressure conditions.

The suction cleaner shown in Figure 1 is representative of a standard type of cleaner consisting generally of a wheeled casing 1 provided with a 40 pivotally mounted handle 2 by which the cleaner is maneuvered over the floor surface. The casing 1 houses the usual suction-creating means including a motor-driven fan rotating at high speed within a fan chamber communicating with 45 a downwardly facing nozzle extending across the forward end of the casing 1. The fan chamber also has an exhaust or discharge passage leading rearwardly and opening into dirt bag 3 having detachable connection at its lower end with a 50 flanged outlet connection 4. The upper end of the dirt bag 3 is attached to the handle 2 through the medium of a detachable fastener which permits the bag to be quickly removed from time to time for the purpose of emptying its contents.

55 The dirt bag 3 is preferably constructed of a

suitable fibrous material of a porous nature capable of filtering out the dirt particles by permitting the passage of the air therethrough. A fabric woven especially for the purpose, is probably the most satisfactory and durable bag material, although it is to be understood that other materials may also be used.

The dirt bag is preferably elongated in the direction of the handle beneath which it is located. Under normal conditions, the bag is distended, 10 but the pressure created is not sufficient to effect the operating efficiency of the cleaner. However, if the bag becomes so filled with dirt that the passage of air through the fabric is restricted, it follows that the internal pressure will increase with a resulting increased back pressure on the suction-creating system and a reduction in its operating efficiency.

The present type of indicator is designed to respond directly to the increased pressure and 20 the accompanying expansive tendency, but inasmuch as the bag material is not inherently elastic, the same effect is obtained by introducing a slight excess of the bag material between the points of attachment of the indicator to the bag. 25

Considering the indicator as a unit separate from the bag, the same comprises two endwise extensible metal sections 5 and 6, having overlapping or telescoping engagement throughout their central portions and held together by interlocking their side edges and against endwise extension by means of a spring 7. These telescoping sections 5 and 6 have the form of elongated plates of thin metal, upset along their longitudinal central portions to provide narrow raised panels and a downwardly facing cavity intended primary to provide space for the spring 7.

In the normal position of the indicator, the outermost section 5 almost completely encloses 40 the innermost section 6 and inwardly from its free end there is provided a rectangular opening 5a through which the raised central panel of the inner section 6 is visible. The outer end portion of each section 5 and 6 slopes off at an angle and merges into end flanges 8, 8 which are provided with pairs of holes 9, 9, by means of which the indicator is removably attached to the bag, as will presently be explained.

A space separates the concealed end of the 50 inner section 6 from the corresponding end of the outer section 5 and within this space is accommodated the coil spring 7, having its ends bent into hooks for attaching to the corresponding ends of the telescoping sections. By prefer- 55

ence, the inner telescoping section 6 carries at its free end, an arm or finger 10 arranged slightly oblique to the axis of the coil spring 7 and provided throughout its length with a series of holes 10a. With the several holes 10a thus spaced, as clearly shown in Figure 3, it follows that by hooking the adjacent end of the spring into one or the other of these holes 10a, it is possible to adjust the spring tension to the particular cleaner on which the indicator is to be used. The outer or free end of the spring 7 is anchored to the adjacent end of the outer section 5 in any suitable manner, as for instance, by slitting and depressing a narrow strip of the metal to form 15 a loop for the outer end of the spring 7, as shown at 11 in Figures 2 and 3.

Bearing in mind that the purpose of the indicator is to inform the operator of the operating conditions, any suitable combination or arrangement of visual signals may be utilized, as for instance, by applying the word "Clean" on the elevated central panel of the lower section 6 so that it normally registers with and is visible through the rectangular opening or window 5a in the outer telescoping section, as shown at 12 in Figure 2. Also, disposed inwardly and beyond the word "Clean" and toward the spring attaching end of the section 6 are printed or stamped the words "Empty bag", as at 13, Figure 2. This latter indication, however, is normally concealed from view but if the sections are extended, the word "Clean" will be replaced by the words "Empty bag" within the window 5a and being seen by the operator is a warning that the bag 35 should be emptied before further cleaning operations are carried on.

But to have the indicator function as intended, it is attached to the bag in a particular way, namely, by having a slight excess or gathering 40 of the bag fabric included between the points at which the ends of the indicator are fastened. Now, as clearly shown in Figure 1, the indicator is arranged circumferentially of the bag and preferably on the top side thereof and adjacent 45 its lower end. Moreover, as shown in Figure 3, the sections of the indicator have a distinct arcuate conformation from end to end so as to conform to the rounded contour of the bag when inflated.

50 In order to properly locate the indicator upon the bag, pairs of fasteners 14, 14 are anchored to the bag material and properly located to make connection with the holes 9, 9 at each end. Thus, the pairs of fasteners 14, 14 are arranged symmetrically with respect to a circumferential line 55 passing around the bag, but more important, the pairs of fasteners are spaced apart circumferentially a distance slightly greater than the distance between the holes 9, 9 at opposite ends of the indicator when retracted. Thus, in applying the indicator to the bag it is necessary to include a slight excess of material between the attaching points, this excess being indicated or represented in Figure 3 by the folds 15, 15.

65 The fasteners 14, 14 may be of any suitable type, as for instance of the kind resembling glove fasteners and consisting of a base 14a having an expandible head adapted to be forced through an opening 9 in the ends of the indicator and preferably surmounted by a detachable button 14b.

70 Thus, once the indicator has been attached and the spring 7 properly adjusted to the pressure conditions of the bag, it follows that as long as the bag does not become filled with dirt to the 75 point of reducing its filtering capacity in an ex-

cessive degree, the cleaner will operate efficiently and the indicator will register "Clean". But should the bag become so full of dirt and litter as to create a condition of excessive back pressure, this condition will be reflected in an increased circumferential expansion of the bag sufficient to overcome the tension of the spring 7, thus causing the telescopic sections of the indicator to elongate and bring the warning signal "Empty bag" into register with the window 10 5a, replacing the safety signal "Clean" which passes beneath the outer end portion of the outer section 5. This extension or elongation of the telescopic sections of the indicator is clearly shown in dotted lines in Figure 3, and is accompanied by the filling out of the bag material between the points of attachment.

A bag pressure indicator of the expandible or extensible type adapted to be removably mounted upon a bag, has the distinct advantage of being relatively inexpensive in its construction and being capable of direct application to the bag, it is possible to consider them as optional equipment since they can be provided or not, as the user may desire, without altering the design of the cleaner body. A further advantage of this particular type of indicator and a detachable mounting is the fact that it can be transferred from one bag to another as they wear out.

Having therefore set forth a practical adaptation of my invention together with the advantages thereof, I claim:

1. In an operating condition indicator for suction cleaners, the combination of a dirt receptacle of flexible material for said cleaner, a pair of extensible telescoping members attached to said receptacle in a manner such that the same tend to extend endwise and display an appropriate signal when the bag is inflated, and tension means opposing the extension of said members until the pressure in said receptacle reaches a predetermined maximum.

2. In an operating condition indicator for suction cleaners, the combination of a dirt bag of flexible material attached to the cleaner, an assembly of extensible parts attached to the material of the bag with sufficient excess of such material between the points of attachment to allow for the relative displacement of the parts when said bag is inflated, tension means acting to oppose the displacement of said parts below a predetermined maximum of internal pressure within said bag, and a signal adapted to be shifted into a visible position under pressures exceeding said predetermined maximum.

3. In an operating condition indicator for suction cleaners, the combination of a dirt bag forming a part of the cleaner assembly, a pair of endwise extensible members attached directly to the bag material with an excess thereof between the points of attachment, and a tension member connecting said extensible member and acting to oppose the extension of said members under normal operating pressures in said bag, one of said members having a normally concealed signal adapted to become visible to the operator upon the extension of said member under a predetermined increase of pressure within said bag.

4. In an operating condition indicator for suction cleaners, the combination of an exposed dirt bag of a flexible material attached to said cleaner, a pair of endwise extensible members having telescopic connection with each other and attached at opposite ends to the bag material with sufficient excess of material between the points 75

of attachment to allow for the extension of said members when the bag is inflated, a tension spring connecting said members and acting to oppose their relative displacement under normal operating pressures in said bag, one of said members having a signal normally concealed by a portion of the other but adapted to be uncovered in the endwise extension of said members under predetermined increased pressure conditions within said bag.

5. An operating condition indicator for suction cleaners, the combination of an exposed fabric dirt bag attached to the cleaner body, a pair of endwise extensible members, a spring connecting said members and adapted to yieldingly resist the extension thereof, said members being attached to the bag with sufficient excess of material between the points of attachment to allow for a limited extension thereof under the 10 circumferential expansion of said bag in its inflated condition, said members including a safety signal adapted to be displayed under normal

pressure conditions within said bag and to be changed to a warning signal when said pressure reaches a predetermined maximum.

6. In an operating condition indicator for suction cleaners, the combination of a dirt bag attached to the discharge outlet of the cleaner, a pair of endwise extensible telescoping sections arranged circumferentially of the bag and fastened at opposite ends thereto with a predetermined excess of the bag material between the 15 points of attachment whereby said members can be extended endwise when said bag is in inflated condition, and a spring connecting said sections together and acting to prevent their relative extension under normal operating pressures in said bag, one of said sections being provided with a warning signal normally concealed from view but adapted to be uncovered in the endwise extension of said sections of a predetermined increase in the internal pressure of said bag. 20
